CENTRIFUGAL SEPARATOR

Curt Roger Adolf Magnus Björnstjerna, Djursholm, Sweden, assignor to The De Laval Separator Company, New York, N. Y., a corporation of New Jersey

Application June 9, 1937, Serial No. 147,244
In Sweden June 26, 1936

3 Claims. (Cl. 233—20)

In separating treatments special difficulties are experienced with regard to the discharge of the heavier component when this is sludge, owing to its high viscosity.

5 To overcome these difficulties several constructions have been suggested, which are based on intermittent opening in the axial direction of the peripheral wall of the sludge space when this has become filled. All of these constructions 10 have the common characteristic that at least one phase hereof (the opening or the closing of the slit in the bowl wall) is effected hydraulically. Further they have the common feature that the movable part or the slide is so placed relative to 15 the other members of the bowl that tightenings must be used between the sludge space of the bowl and the hydraulic pressure-chamber. The disadvantages of this are evident: as a completely tight joint can never be obtained with packings 20 of this type, first, regulating liquid penetrates into the sludge space, a contamination of the sludge and the separated liquid thereby also taking place, and secondly, sludge may penetrate into the pressure chamber and contaminate the 25 regulating liquid; this sludge finally causes objectionable wear of the tightening mechanism and the guiding surfaces of the slide.

The difficulties referred to above in a separator are eliminated by the means shown in the 30 accompanying drawings, in which:

Fig. 1 is a sectional view of a bowl formed in accordance with the invention; and

Figs. 2, 3 and 4 are similar views of modified forms of bowls.

35 As shown by Fig. 1 the unseparated liquid flows through the tube 1 into the chamber 2 provided in the nave 3 of the bowl, whence it proceeds through the openings 4 and the channels 5 in the distributor 6 into the sludge space 7, which is 40 formed by the fixed hood 8 and the movable slide 9. The heavier sludge particles are immediately separated here. A finish separation is then effected in the spaces 10 between the discs 11, the purified liquid then leaving the bowl through the 45 holes 12 and the sludge flowing into the sludge space 7. Into the chamber 14 formed between the slide 9, which is movable in axial direction on the nave 3, and the member 13 which is fixed to the said nave, regulating liquid is supplied 50 through the channels 15 and 16, the said chamber 14 thereby being filled. At the periphery of the slide 9 openings 17 are provided for the discharge of the liquid, the dimensions of these 55 openings being such that less liquid discharges therethrough than is being supplied. They are

provided for the purpose of emptying the chamber 14 when the supply through 16 ceases. Owing to the centrifugal force the axial pressure of the liquid contained in 14 becomes greater than that in the sludge space 7 and also directed in the 5 opposite direction. Because of this the slide 9 is pressed up against the hood 8 and makes a tight joint with the tightening device 18 in the hood, so that the slit 19 between the slide and the hood is shut. Level outlets 20 are also provided which insure that the chamber 14 can never become filled further towards the center than to the said outlets.

When the chamber 7 has become filled with sludge this must be discharged which may be 15 effected in several ways. According to Fig. 1 a member 21 is fixed to the slide 9 and between the said member and the member 13 a chamber 22 is formed. This is filled with liquid through a tube 23 at the same time as the supply to the chamber 14 is interrupted. The chamber 14 is 20 emptied through the channels 17 and the slide 9 is pressed downwards by the liquid in the chamber 22, thereby opening the slit 19 and the sludge flows out. During this period the supply through tube 1 should suitably be interrupted. The tube 23 is now closed, the liquid contained in chamber 22 is drained thru the openings 24, the chamber 14 is filled again and the slide moves upwards. In order to prevent leakage from 14 to 22, packings 25 and 26 having an outlet 27, are provided. 30

The emptying may also be effected according to Fig. 2. Between the slide 9 and the nave 3 a spring 28 is provided which tends to press the slide 9 downwards. When the chamber 14 has 35 been emptied of liquid by closing the supply 15, the axial upwardly directed pressure on the slide disappears, and the spring presses it down. Both the member 21 and the spring 28 may be dispensed with, the liquid pressure present in the 40 sludge chamber thereby effecting the opening.

Fig. 3 shows a modification of Fig. 1. The drain channels 17 are not provided. When the chamber 14 is filled, the excess liquid flows out through the channel 20a. The dimensions of 45 this channel are such that it can only take the normal flow through 15, which exists during the period when the sludge space is closed. If now the flow through the inlet 15 is increased, the liquid is forced to flow through the channel 29 50 into the chamber 22 which is thus filled. As the pressure in this chamber is greater than in 14, the slide 9 is forced down. The liquid contained in 14 thereby partly discharges through the channel 20a and partly flows into the chamber 22 55

through the channel 29. The figure shows that the separating chamber and the pressure chamber at the periphery are entirely separated. At the nave the conditions are the same as the guiding surface of the slide is here positioned inside 5 the surface of the liquid layer.

There may be a possibility that the sludge and the regulating liquid are mixed the one with the other after they have left the bowl. This would 10 take place through leakages between the collecting vessels for the different constituents. There is in fact a risk of such leakages owing to the powerful air currents which are produced by the fan action of the bowl which is considerable at the radius it has in the present case. 15 These air currents may however be reduced by known arrangements, for instance by providing wings on the covers. Another method is to let the edge of the covers approach the rotation 20 center as much as possible.

According to Fig. 4 the latter alternative has been used. The operation of the separator is in principle the same as above. As shown in the figure, however, the bowl spindle, the nave 25 3a and the distributor 6a are integral. The slide 9a still forms the bottom of the sludge chamber 1a, but the pressure chambers 14a and 22a are located in a chamber below the bowl and separated therefrom by the cover 30 which extends 30 towards the center, the cover at the same time also forming a bearing 31 for the revolving parts 35 of the separator. In order to enable construction the slide 9a has been provided with an extra part 29a. With the small diameter of the bearing 31 there are no difficulties in preventing air currents from passing through. The opening and closing part works in another chamber which is separated from the separating part of the bowl.

What I claim and desire to protect by Letters 40 Patent is:

1. A centrifugal separator including a bowl comprising an axially fixed wall member and an axially movable wall member having peripheral engaging portions and shaped to provide a separating chamber having a sludge space adjacent the peripheral engaging portions and arranged to be closed by their engagement, and means for axially moving the movable wall member to effect opening and closing of the sludge space, 45 said means comprising an annular skirt extending axially from the side of the movable member exteriorly of the bowl, a fixed wall member

engaging the annular skirt and forming therewith a pressure chamber, and means for introducing fluid into said pressure chamber to control movement of the movable wall member.

2. A centrifugal separator including a bowl having a separated liquid outlet relatively near its axis of rotation and comprising an axially fixed wall member and an axially movable wall member having peripheral engaging portions and shaped to provide a separating chamber having a sludge space adjacent the peripheral engaging portions and arranged to be closed by their engagement, and means for axially moving the movable wall member to effect opening and closing of the sludge space, said means comprising an annular skirt extending axially from the side of the movable member exteriorly of the bowl, a fixed wall member engaging the annular skirt and forming therewith a pressure chamber, and means for introducing fluid into said pressure chamber to control movement of the movable wall member, said movable wall member being imperforate from a radius less than that of said liquid outlet to a point at the periphery thereof a substantial axial distance from the engagement of said peripheral engaging portions. 10 15 20 25

3. A centrifugal separator including a bowl having a separated liquid outlet relatively near its axis of rotation and comprising an axially fixed wall member and an axially movable wall member having peripheral engaging portions and shaped to provide a separating chamber having a sludge space adjacent the peripheral engaging portions and arranged to be closed by their engagement, and means for axially moving the movable wall member to effect opening and closing of the sludge space, said means comprising a cylindrical surface extending axially from the side of the movable member exteriorly of the bowl, a fixed wall member engaging said 30 35 40 45 cylindrical surface and forming therewith a pressure chamber, and means for introducing fluid into said pressure chamber to control movement of the movable wall member, said movable wall member being imperforate from a radius less than that of said liquid outlet to a point at the periphery thereof a substantial axial distance from the engagement of said peripheral engaging portions.
